UNITED STATES PATENT OFFICE.

JOHN H. SHAW, OF NEW HAVEN, CONNECTICUT, ASSIGNOR TO THE SARGENT & COMPANY, OF SAME PLACE.

CYLINDER-LOCK.

SPECIFICATION forming part of Letters Patent No. 446,176, dated February 10, 1891.

Application filed December 8, 1890. Serial No. 373,911. (No model.)

To all whom it may concern:

Be it known that I, JOHN H. SHAW, of New Haven, in the county of New Haven and State of Connecticut, have invented new Improvements in Cylinder-Locks; and I do hereby declare the following, when taken in connection with accompanying drawings and the letters of reference marked thereon, to be a full, clear, and exact description of the same, and which said drawings constitute part of this specification, and represent, in—

Figure 1, a perspective view of the cylinder after the guard-recesses are formed, but before the key-hole is cut; Fig. 2, a perspective view of the same after the key-hole is cut; Fig. 3, a perspective view of one of the guards detached; Fig. 4, a perspective view of the cylinder with the guards introduced; Fig. 5, a longitudinal central section of the cylinder through the key-hole, showing one of the guards; Fig. 6, opposite side views of the key; Fig. 7, a transverse section through the cylinder cutting through the guards, showing the key in place; Figs. 8, 9, 10, and 11, modifications.

This invention relates to an improvement in that class of cylinder-locks in which the cylinder is adapted to receive a thin flat key, and particularly to that class in which the key-hole is provided with inward projections or guards, so as to require that corresponding grooves be made in the sides of the key, the invention relating particularly to the formation of such inward projections in the key-hole. These projections or guards are usually formed as an integral part of the cylinder—that is, of the same metal as the cylinder, and this metal is of a soft nature, so as to easily wear away or be removed by evil-disposed persons, it being understood that these projections into the key-hole aid very much in protection against tampering with the lock. Again, the formation of the key-hole with the inward projections as an integral part of the cylinder adds materially to the cost of manufacture.

The object of my invention is a construction which will permit such projections to be introduced after the key-hole is formed, and so that they may be made from a metal much harder than the metal of the cylinder; and

the invention consists in forming a longitudinal recess in the cylinder upon the side of the key-hole where the projection is to be applied, the said recess being undercut, and then introducing into said recess a piece of metal in shape corresponding to the said undercut recess, but of a size to give the required projection into the key-hole and as more fully hereinafter described.

A represents the cylinder, which is of the usual external form.

In the best method of preparing the cylinder to embody my invention holes *a b*, more or less in number, are bored longitudinally into the front end of the cylinder before the key-hole is cut and at points corresponding to the position required for the projections or guards of the cylinder, and they are in such position with relation to the key-hole that when the key-hole *B* is cut, as seen in Fig. 2, it will cut away less than one-half of the said holes *a b*, as seen in Fig. 2, leaving longitudinal recesses at the sides of the key-hole of somewhat more than half a circle in transverse section.

From hard steel or other suitable wire of a diameter corresponding to the diameter of the holes *a b* pieces *d* are cut, as seen in Fig. 3, and these pieces are driven into the recesses *a b* of the sides of the key-hole, as seen in Fig. 4, and because the metal of the cylinder embraces more than one-half the cylindrical pieces thus introduced, those pieces are firmly held in their places and project into the key-hole, so as to form guards upon the sides of the key-hole, as seen in Figs. 4 and 5, there being two guards, one upon each side, as shown in Fig. 4. The key requires to be correspondingly constructed, as seen in Fig. 6. On one side the key is constructed with a longitudinal groove *e*, which corresponds to the guard on one side, and with a groove *f* corresponding to the guard of the other side, and so that when the key is introduced, as seen in Fig. 7, these grooves will pass onto the respective guards, as shown in that figure. In the case of a key of serpentine shape in transverse section, as seen in Fig. 8, the guards will be introduced accordingly and as seen in that figure. In some cases a single guard on one side only is all

that is required, but as many guards may be introduced as desirable.

While I prefer to make the guards from wire or pieces of cylindrical shape, so that 5 holes may be bored into the cylinder before the key-hole is cut, the guards may be made of other shape—as, for illustration, dovetail shape, as seen in Fig. 9. Then after the key-hole is cut, as seen in Fig. 10, longitudinal 10 undercut grooves are cut in the sides of the key-hole, as represented in Fig. 11. In this case the guards have the advantage of being made from hard metal, and the undercut grooves serve to hold them firmly in place, 15 and it permits the same formation of the key-hole by a simple cut, as in the first illustration. I therefore, while preferring the cylindrical shape of the guards and the corresponding undercut or cylindrical-shaped grooves 20 or seats in the cylinder for the guards, do not wish to be understood as limiting the invention to the particular shape of the guards. By this construction the key-hole may be cut through the cylinder as if it were a plain flat 25 key-hole, and the guards thus made independent of the cylinder may be made from a hard metal, so as to avoid the wearing away

which necessarily follows where the guards are made as an integral part of the softer-metal cylinder.

30

1. In a cylinder-lock in which the cylinder is constructed with a longitudinally flat key-hole, the key-hole constructed with one or more longitudinal undercut grooves upon its sides, combined with guards of corresponding 35 shape set in said grooves, substantially as described.

2. In a cylinder-lock in which the cylinder is constructed with a longitudinal flat key-hole, the key-hole constructed with one or 40 more longitudinal recesses in its sides, the said recesses being somewhat more than half a circle in transverse section, combined with guards of corresponding but of substantially 45 full cylindrical shape set into said recesses in the said cylinder, substantially as described.

In testimony whereof I have signed this specification in the presence of two subscribing witnesses.

JOHN H. SHAW.
